UNITED STATES PATENT OFFICE.

FRIEDRICH SPEIDEL, OF PFORZHEIM, GERMANY.

ORNAMENTAL LINK STRUCTURE.

Application filed August 25, 1928. Serial No. 301,967.

The present invention has reference to improvements in the art of building up link structures, and relates more specifically to flexible bands, especially for personal adornment, such as bracelets, anklets, wrist watch straps, and the like, and the particular object of the invention is to provide a structure of this general character in which the individual links are interconnected in flexible relation by means of separate connecting members in such manner that the latter are completely hidden from view.

My invention will best be understood when described with reference to the accompanying drawing, in which Fig. 1 is a front elevation of a blank for forming an outer link member; Fig. 2 is an edge view thereof. Figs. 3 and 4 are similar views at a later stage of working the blank; Figs. 5 and 6 respectively show an intermediate or connecting member in front and edge views. Fig. 7 shows a box-shaped link, formed by doubling over a blank, and Fig. 8 is an edge view thereof. Fig. 9 shows two blanks connected by a connecting member, and Fig. 10 is a section on line 10—10 of Fig. 9, on an enlarged scale. Fig. 11 shows a portion of the finished flexible structure.

The individual links are formed from blanks punched out of sheet material. As shown, by way of example, the one half 1 of each blank is provided with straight edges, and the other half 3 with ornamental edges, whereby a scaly effect is produced in the finished product. I do not, however, restrict myself to the particular edge conformation shown, and obviously, may employ other edge forms on the one blank half for producing other ornamental effects.

The blank half 1 is designed to form the inner wall, and the blank half 3 the outer wall of the finished link.

In the next operative step the two narrow longitudinal portions 4 of the blank-half 1 between the offsets 2 are bent up at a right angle, as is also the upper cross-edge 5 of part 3, as shown in Figs. 3 and 4.

The intermediate members or connectors 7 (Figs. 5 and 6) are elongated metal plates provided with a slot 6, which are preferably likewise punched from sheet metal.

In the next step the blanks 1, 3 are folded over along weakened lines 8 (Fig. 9) to form flat boxes (Figs. 7 and 8), the part 3 forming the outer face, the part 1 the inner wall, the upbent edge 5 one short cross-wall, and the blank portion 9 between the weakened lines 8 the other short cross-wall, as shown in Fig. 8, the upbend ledges 4 partly forming the longitudinal side walls. The final step is the shutting of the link, which is done by soldering the part 5 to the contacting edge of the part 1. But before the link is shut, in fact, before it is formed by doubling over, it must be connected at one or both longitudinal sides to the adjacent link or links. For this purpose two such link members are placed close to one another, as shown in Figs. 9 and 10 and a slotted connecting member 7 is inserted so that the respective abutting ledges 4 of the boxes extend upwardly into and through the slot 6 of the connector. The latter is preferably of somewhat thicker stock than the link stock so as to snugly fit the cross-section of the boxes to prevent the latter from becoming deformed in normal use. The individual links are thus readily concatenated, as it were, the ornamental face portions 10 closely but freely interfitting (Fig. 11). As the last step each link is then solder-shut 80 along the edge 5.

To the ends of the concatenation, finally, are secured the snap links or other locking member for closing the structure to form a circlet, or other end members in the case of watch fobs or the like.

The intermediate members or connectors 7, as will readily be understood, are completely hidden in any position of use of the finished link structure, and for that reason they may be made of cheap stock, whereas the links will generally be of precious or semi-precious or plated material.

If the ornamental face of the links presents wavy, sharply pointed or like ornamental edges, these latter are effectively supported or backed by the ledges 4 and the connectors 7, so that they are not apt to become deformed under inwardly directed pressure.

The outer faces of the link walls 3 may be engraved, enameled, jeweled, or otherwise adorned in any desired manner.

Having thus described my invention, I claim:—

A link band structure comprising a plurality of link members each formed from an elongated strip of sheet metal doubled upon itself and comprising front and rear walls connected at their ends, one of said walls being provided with locking flanges on opposite

sides of the longitudinal center thereof, and intermediate members disposed between the 10 walls of adjacent link members, each link member having a slot therein receiving the adjacent flanges upon the adjoining edges of the link members.

FRIEDRICH SPEIDEL.
